ARC-TRAPPING IMPROVEMENT FOR ELECTRIC
SWITCH CASES

BACKGROUND OF THE INVENTION

1. FIELD OF THE INVENTION

This invention relates to electric switches and, more particularly, to lever or slide switches enclosed within a switch case and operated by a manual actuator element or the like extending through an opening in the switch case. An important feature of the invention is the provision of means for trapping or diverting an arc discharge generated by the opening of a circuit within the switch case in order to protect not only the other components of the switch, especially the actuator, but also to protect the operator of the switch from any injury that might otherwise be caused by the arc discharge.

2. Description of the Prior Art

Applicant is aware of the following U.S. Pats. Nos. 2,399,462; 2,521,468; 3,174,002; 3,177,325; 3,223,794; 3,259,723 and 3,328,540.

None of said patents discloses a switch having a downwardly extending barrier or shield-forming recesses at the ends of a closure plate located directly above the circuit contact elements for trapping an arc discharge produced by the opening of electric circuits within the switch case.

It has been found that in toggle switches such as those disclosed in U.S. Pats. Nos. 3,031,547 and 3,165,604, where pivoting levers alternatively make and break electrical circuits within the switch case, an arc discharge is generated upon the opening of an electrical circuit which causes a spark to travel upwardly towards the cover plate of the switch case and to impinge upon the shank or handle of the manually operated toggle or slide actuator which could give the operator an electric shock which is either mild or severe, depending upon the voltage of the circuits controlled by the switch.

SUMMARY OF THE INVENTION

In order to obviate the occurrence of possible injury to the operator of the switch or damage to the switch components, the structure of the switch is improved by forming one or more downwardly extending bosses on the cover plate or roof portion of the switch case surrounding the aperture through which the actuator extends thereby providing a barrier or shield against which the spark is quenched or deflecting the latter harmlessly onto the metal pivoting lever contact element. The upward path taken by the arc discharge toward the cover plate has been confirmed by the fact that after use of the switch for a period of time, the interior of the cover plate directly above the circuit contact element becomes charred, thereby indicating that the arc discharge is of such power that it does not become quenched by the metallic pivoting lever contact element that moves away from the circuit element when the respective circuit is opened.

By providing the insulating shield or barrier around the opening in the cover plate or roof portion by means of integral molding or the like and extending it inwardly into the interior of the switch case to a distance sufficient to protect the shank or handle of the actuator element, the improvement has effectively eliminated any possibility of an arc discharge reaching and damaging said actuator element and injuring the operator.

The purpose of the arc barrier is to divert the arc discharge in such a way as to cause it to take a longer path, and if the discharge is long enough, it will be deflected harmlessly back to the lever or slide contact in the interior of the switch. Thus, a switch with the arc discharge barrier and deflector of the present invention is able to carry higher electrical loads than was possible without such an improvement and without increasing the size of the switch. Also, if the improved arc discharge trap or deflector were not incorporated into the electrical switch and if a portion of the actuator shank or handle is made of metal, an electrical short could be caused with possible injury not only to the operator but also to the product in which the switch is installed. If the actuator and its shank or

handle is made of materials other than metal, the trapping or deflection of the arc by the structure of the present invention prevents possible deterioration of the actuator and eventual failure of the switch from such deterioration.

5 In a second embodiment of the invention, wherein the switch case is made of an assembly of a pair of identical switch case sections, where a median seam line exists between the juxtaposed sections into which an arc discharge might penetrate, the two molded sections are constructed so as to provide for interfitting portions at the seam line adjacent the arc discharge barrier so that the arc will still be trapped and deflected without being permitted to escape from the switch case through said seam line.

10 15 These and other novel features and advantages of the present invention will be described and defined in the following specification and claims.

BRIEF DESCRIPTION OF THE DRAWING

20 FIG. 1 is an external perspective view of a typical electric switch assembly embodying the present invention;

25 FIG. 2 is a greatly enlarged vertical central section view taken on line 2—2 of FIG. 1, some parts being shown in elevation and some parts in dotted outline;

30 FIG. 3 is a vertical fragmentary section view taken on line 3—3 of FIG. 2;

35 FIG. 4 is a view taken on line 4—4 of FIG. 2, some parts being omitted;

30 FIG. 5 is a perspective view of a component in the embodiment shown in FIG. 4;

35 FIG. 6 is similar to FIG. 5, disclosing another embodiment of said component of the invention;

40 FIG. 7 is a fragmentary view similar to FIG. 2 showing the manner in which a spark is trapped according to the present invention;

45 FIG. 8 is a vertical section view, some parts in elevation and some parts in dotted outline, illustrating an alternative embodiment of the invention;

40 FIG. 9 is a view taken on line 9—9 of FIG. 8;

45 FIG. 10 is a perspective exploded view of the switch case sections of the embodiment shown in FIGS. 8 and 9; and

50 FIG. 11 is a top exploded view of the switch case sections shown in FIG. 10.

45 DESCRIPTION OF THE PREFERRED EMBODIMENTS

55 Referring now to the drawing in detail, the switch of the present invention comprises a boxlike molded case generally designated 21, made of a suitable electrically insulating material such as Bakelite, synthetic resin, or the like, and having a pair of spaced-apart opposing end walls 22 and a pair of spaced-apart opposing sidewalls 23. The bottom of case 21 is enclosed by a floor 24.

55 The open top of case 21 is covered by a closure plate or roof element 26 made of a suitable insulating material, said closure plate having integrally formed, downwardly extending shoulders 27 which fit snugly between the upper interior portions of walls 22 and 23 to facilitate the location of said closure plate over the open end of case 21. See FIGS. 2 and 5. Closure plate 26 is retained in position on case 21 by means of a plate 28 extending over the top central portion thereof, said plate 28 having a pair of downwardly extending spaced-apart integrally formed leaves 29 that fit within suitable recesses in closure plate 26 and the sidewalls 23, said legs terminating in clamping lugs 31 that extend over the bottom of case 21 to secure the assembly in position. Plate 28 has a central aperture in which is mounted the lower end of an upwardly extending tubular threaded bushing 32.

60 65 70 The interior wall of bushing 32 has an inwardly curving annular shoulder 33 intermediate its ends, said shoulder being adapted to cooperate with a toggle or actuator element 34, a portion of whose surface is curved to mate movable with said shoulder, whereby said toggle may move pivotally relative to said bushing. Toggle 34 has an upwardly extending handle 36

75

for manual operation and a lower tubular shank extension 37. Handle 36 has a bore 38, toggle has a bore 39, and extension 37 has a bore 41, all of said bores being axially aligned with each other. Bores 39 and 41 longitudinally accommodate an elongated control pin 42 which is normally urged downwardly and outwardly from bore 41 by captive spring 43 located within bores 38 and 39. Control pin 42 is made of a suitable electrically insulating material such as Bakelite, nylon, or the like, and has an integrally formed outer end of slightly reduced diameter in the form of a smoothly rounded nib 44 extending downwardly to actuate the movable circuit contact lever of the switch, as will be described hereinafter. While nib 44 is being urged downwardly against the circuit lever, spring 43 acting upon the upper end of bore 38 urges toggle 34 upwardly and snugly against shoulder 33 without preventing pivotal motion of said toggle relative to bushing 32.

Positioned in and extending through floor 24 is a pair of spaced-apart electrically conducting studs 46 and 47 which have respective electrically conducting contact heads 48 and 49 extending into the interior of case 21. The lower ends of said studs on the outer surface of floor 24 have respective rivet heads 51 and 52 to which are firmly secured electrically conductive lugs 53 and 54, respectively, which serve as terminals to which separate electrical circuits are connectable.

Positioned intermediate studs 46 and 47 is an electrically conducting stud 56 which also extends through floor 24. The lower end of stud 56 below the bottom of floor 24 has a rivet head 57 to which is firmly secured an electrically conductive downwardly extending terminal lug 58 to which is connectable an electric circuit that is common to the other two circuits that are controlled by the switch herein. The upper end of stud 56 terminates in the form of a rivet head 59 which secures the base of an electrically conducting support or yoke 61 to the inner surface of floor 24 of case 21.

Yoke 61 has a pair of integrally formed, spaced-apart, upwardly extending arms 62, each of which terminates in a pair of spaced-apart short fingers 63. Between each pair of fingers 63, the upper edge of arms 62 form shoulders 64 which serve as spaced apart fulcrums for an electrically conductive V-shaped circuit contact lever 66 freely supported pivotally thereon. Circuit contact lever 66 has a pair of integral lever arms 67 and 68 extending in opposite directions and arrayed at an angle relative to each other.

The central arcuate portion of circuit contact lever 66 is positioned between arms 62 of yoke 61. Connected to the outer end portions of lever arms 67 and 68 are contact buttons 71 and 72, respectively. Upon the pivoting motion in opposite directions of lever 66, contact buttons 71 and 72, respectively. Upon the pivoting motion in opposite directions of lever 66, contact buttons 71 and 72 make or break electrical connections with contact heads 48 and 49, respectively.

Pivotal motion is imparted to lever 66 by the reciprocating action of toggle 34 which causes nib 44 to move longitudinally along said lever and ultimately along arms 67 and 68 alternatively for closing and opening respective pairs of contacts 48-71 and 49-72. Assuming that lug 58 is connected to the powerline of a source of electrical power, the switch opens and closes the respective circuits to which lugs 53 and 54 are connected.

Upon the opening of either pair of contact buttons 48-71 or 49-72, when the respective electrical circuit is broken there is an accompanying arcing phenomenon that takes place whereby a spark generated between the moving-apart contacts normally is pulled upwards by the moving contact on lever 66 and would normally short out against extension 37 as the latter moves from the end of arm 67 toward the center of lever 66. Since extension 37, toggle 34, and handle 36 may be made of metal, this arcing action is obviously undesirable because of the possible injury that can be imposed upon the operator of the switch. If the toggle or actuator is made of nonmetallic material, the arc discharge may cause deterioration of the actuator, thereby resulting in failure of the switch.

Accordingly, in order to obviate these potential dangers, the central portion of closure plate 26 has an integrally formed, downwardly extending boss 73 that surrounds the elongated aperture 74 within which toggle extension 37 moves longitudinally. Said boss 73 forms a protective barrier or skirt around toggle extension 37 and extends a sufficient distance into the interior of case 21 whereby an arcing spark generated by the opening of a pair of contacts is prevented from reaching or impinging upon said extension, as shown in FIG. 7. The arrows in FIG. 7 indicate schematically the path of the arcing spark as it is deflected away from extension 37 and back upon the outer end portion of lever arm 67 where it is harmlessly quenched.

In an alternative embodiment as shown in FIG. 6, the arc trap is formed by a pair of spaced-apart substantially parallel integrally formed, downwardly extending bosses 76 made of insulating material which serve effectively to shield extension 37 from any spark generated by the separating electrical contacts. Bosses 76 extend laterally between the interior surfaces of sidewalls 23.

In both embodiments shown in FIGS. 5 and 6, the respective shields or barriers are spaced apart from the respective top end regions of the switch case whereby they form an arc-trapping compartment located substantially directly above the respective circuit element positioned at a corresponding bottom end region of the switch case.

A further embodiment of the invention is shown in FIGS. 8-11 wherein the case of the switch comprises a pair of identically formed as sections 80 made of a suitable insulating material such as Bakelite, nylon, or the like. Each section 80 comprises a sidewall 81, a pair of end walls 82, a floor 83, and a roof 84. One end of floor 83 has a laterally extending recess 86 while the other end thereof has a laterally extending integrally formed projection 87, said projection 87 interfitting with a corresponding recess 86 for proper alignment of the two sections 80 when they are juxtaposed to form a switch enclosure, as shown in FIGS. 8 and 10.

One end portion of roof 84 has a surface recess 88 while the other end portion of said roof has an integrally formed projection 89. When two sections 80 are juxtaposed, each projection 89 is nested within a corresponding recess 88 to form an overlapping protective barrier across the seam line 91 formed between the adjacent case sections 80.

Floor 83 of each section 80 has three lateral slots 92, 93 and 94, which frictionally accommodate the upper portions of terminals 96, 97 and 98, respectively. Movable slidably across the upper ends of terminals 96, 97 and 98, is a switch lever 101, said lever having a centrally indented recess 102 in which is nested the lower end of nib 103 movable longitudinally within the lower stub end portion 104 of a toggle element 106. Nib 103 is yieldably urged downwardly upon lever 101 by means of captive spring 107 within toggle arm 106. Intermediate the ends of toggle 106 is an integrally formed enlarged curved portion 108 which moves pivotally within the curved throat 109 of bushing 111 mounted on top of the juxtaposed case sections 80 by means of a cover plate 112. Cover plate 112 has a pair of integrally formed leaves 113 which extend down the respective external sides of case sections 80 and terminate in fingers 114 that are forced inwardly into suitable recesses 116 in the bottom of sections 80 to retain said cover plate and bushing in position. The upper end of terminal 97 has a suitable central recess whereby the bulge formed by recess 102 in lever 101 may pass freely therethrough when said lever is moved from one switching position in contact with terminal 96 to another switching position in contact with terminal 98 and vice versa.

The roof portions 84 each have elongated lateral recesses 117 which together form a single slot within which stub 104 can move freely longitudinally.

Integrally formed on the bottom surfaces of roofs 84 of case sections 80 at the respective ends of recess 117 are laterally and downwardly extending bosses 118 which serve as arc barriers in the same manner as bosses 73 and 76 in FIGS. 2 and 6,

respectively, in the other embodiments of this invention. Bosses 118 form a protective barrier for toggle stub 104 whereby an arcing spark generated by the opening of switch lever 101 in respect of terminals 96 or 98 is prevented from reaching or impinging upon said stub as shown in the left hand portion of FIG. 8. The arc discharge is effectively trapped or deflected by said barriers or bosses 118 and rendered harmless.

In the embodiment of the invention shown in FIGS. 8-11 in which the two identical case sections 80 are made by a single mold whereby considerable economies are realized, the possibility of arc leakage through a central seam 91 between the two sections is prevented by the overlap of projections 89 into respective recesses 88 so that the arc cannot escape through the seam. At the same time, the arc is entrapped by the 15 downwardly extending bosses 118 formed on the bottom surfaces of roofs 84 of case sections 80 in the same manner as shown in FIG. 7 in the other embodiment of this invention.

Although the drawings illustrate a toggle actuator for the switches shown therein, the present invention contemplates that other types of actuators may be used, such as sliders, pushers, triggers, or the like, without departing from the concepts and intention of the invention herein.

Although the present invention has been described with reference to particular embodiments and examples, it will be apparent to those skilled in the art that variations and modifications can be substituted therefor without departing from the principles and true spirit of the invention.

I claim:

1. An electric switch comprising a boxlike case, at least one electrical circuit element in said case, a contact element within said case movable between alternative positions into contact with and apart from said circuit element for closing and opening its electrical circuit, the opening of said electrical circuit normally producing an arc discharge between said circuit element and said contact element, a roof portion made of insulating material enclosing the top of said case, an actuator element extending from the exterior of said case through said roof portion into the interior of said case for producing the switching motion of said contact element, and a shield of insulating material on said roof portion surrounding the area where said actuator element extends through said roof portion and extending partially into the interior of said case, said shield being located in a position near the end region of the case to form an arc-trapping compartment located substantially directly above said circuit element and causing an arc spark to be deflected and to be quenched upon the outer end portion of said contact element, said shield forming a barrier between said arc discharge within said case and said element.

2. A switch according to claim 1 and further comprising a slot in said roof portion within which said actuator element is movable from one switch position to another and wherein said shield comprises a boss integrally formed on said roof portion around said slot and extending into the interior of said case a sufficient distance to prevent an arc discharge formed by the opening of said electrical circuit to impinge upon said actuator element.

3. A switch according to claim 1 and further comprising a slot in said roof portion through which said actuator element extends and wherein said actuator element is made of metal and said shield extends into the interior of said case and forms a skirt around that portion of the actuator element that extends into the interior of said case a sufficient distance to prevent an arc discharge formed by the opening of said electrical circuit to impinge upon said actuator element.

4. A switch according to claim 1 and further comprising a slot in said roof portion through which said actuator element

extends and wherein said actuator element is made of metal, and said shield comprises a pair of spaced-apart laterally extending bosses formed on said roof portion at opposite ends of said slot, said bosses extending downwardly into the interior of said case a sufficient distance to prevent an arc discharge formed by the opening of said electrical circuit within the interior of said case impinging upon said actuator element.

5. A switch according to claim 1 wherein there are two spaced-apart electrical circuit elements mounted in the interior of said case and wherein said contact element comprises a lever pivotally mounted between said two circuit elements, said lever being movable into alternative positions for closing the electrical circuit of one of said circuit elements, and opening the electrical circuit of the other of said circuit elements.

6. An electric switch according to claim 1 wherein said circuit element is located at the bottom end region of said case and said shield is located in a position spaced apart from the top end region of said case to form an arc-trapping compartment substantially directly above said circuit element.

7. An electric switch according to claim 1 wherein said case comprises a pair of identically formed sections juxtaposed against each other to form said case, an opening in the top of said case through which said actuator element extends, a recess in one end portion of the roof portion of each of said sections, an integrally formed projection in the other end portion of said roof portion, the roof portion projection of each of said sections nesting within the roof portion recess of the adjacent case section whereby a barrier is formed across the central seam line between said juxtaposed case sections to prevent arc discharge from penetrating into and through said seam line, and integrally formed laterally extending bosses formed at the opposite ends of said opening, said bosses extending downwardly into the interior of said case a sufficient distance to prevent an arc discharge formed by the opening of an electrical circuit within the interior of said case from impinging upon said actuator element.

8. An electric switch in the form of a boxlike case enclosing electrical switching elements, said case comprising a pair of juxtaposed identically formed case sections formed of insulating material and forming a seam line therebetween, at least one electrical circuit element in said case, a contact element within said case movable between alternative positions into contact with and apart from said circuit element for closing and opening its electrical circuit, the opening of said electrical circuit normally producing an arc discharge from between said circuit element and said contact element, the top portions of each case element together forming a roof enclosing the top of said case, an actuator element extending through said roof into the interior of said case for producing the switching motion of said contact element, a barrier integrally formed on the interior surface of said roof and extending inwardly into the interior of said case surrounding the area where said actuator extends through said roof, said barrier being located in a position near the end region of the case to form an arc-trapping compartment located substantially directly above said circuit element and causing an arc spark to be deflected and to be quenched upon the outer end portion of said contact element, said barrier acting as a shield between said arc discharge within said case and said actuator, an integrally formed projection on the top of one end of each case section and a recess in the top of the other end of each case section, said respective projections being nested in respective recesses to extend over the seam line between said case sections and in the region above the contact element where arc discharge takes place 60 whereby said discharge is prevented from penetrating into and through said seam line.
